INVENTOR:

Martin Bernard Moshel

UNITED STATES PATENT OFFICE

160,000

WATCHCASE

Martin Bernard Moshel, Brooklyn, N. Y.

Application November 15, 1949, Serial No. 6,061

Term of patent 14 years

(Cl. D42—8)

To all whom it may concern:

Be it known that I, Martin Bernard Moshel, a citizen of the United States, residing at Brooklyn in the county of Kings and State of New York, have invented a new, original, and ornamental Design for Watch Cases, of which the following is a specification, reference being had to the accompanying drawing, forming part thereof.

Fig. 1 is a front perspective view of a watch case, showing the essential features of my design in full lines.

Fig. 2 is a side elevational view of the same.

I claim:

The ornamental design for a watchcase as shown and described.

MARTIN BERNARD MOSHEL.
